Attorney.

UNITED STATES PATENT OFFICE.

DAVID ZAIDEN, OF EAST ORANGE, NEW JERSEY.

TOY.

1,368,592.

Specification of Letters Patent. Patented Feb. 15, 1921.

Application filed May 24, 1919. Serial No. 299,567.

To all whom it may concern:

Be it known that I, DAVID ZAIDEN, a citizen of Russia, residing at East Orange, county of Essex, and State of New Jersey, have invented certain new and useful Improvements in Toys, of which the following is a specification.

This invention relates to toys and especially to figures of doll babies or animals having limbs adapted to move freely and carried by or connected with the armature of an electromagnet, the object of the invention being to energize the magnet and by an intermittent current to give movement to the limbs to simulate life, as will be more fully described in the following specification, set forth in the appended claims and illustrated in the accompanying drawings, wherein:

20 Figure 1 is a face view of a doll with the improvements and the invention applied thereto.

Fig. 2 is a vertical sectional view of the doll.

25 Fig. 3 is a sectional detail of the connections between a pair of limbs.

While the figure of a doll is shown in the drawings it is evident that other shapes or animals may be represented in metal, papier mâché or other substances and having limbs 30 adapted to move and be actuated by an electric current.

The doll 5 as illustrated has the arms 6 at each side and they are connected by a spring 35 7 attached to the hooks 8 on each arm and which tends to draw them together. Tubes 9 surround the spring and fit over a central tube 10 through which the spring 7 also passes but which is hung on a rod 11 carried

40 by the armature 12 of the electric magnet 13 and when the latter is energized the armature is set in motion, the arms 6 are agitated and the effect is increased by the resiliency of the spring 7 which allows a 45 freedom of movement to the arms and at the same time permits of their adjustment to any position with relation to the body 5.

The tubes play through perforations 14 and an intermittent electric current through 50 the means of the circuit breaker 15 causes an oscillating movement by the said tubes and a shaking of the arms and any garment which might be worn by the figure. The electric current for the toy may be provided 55 by a battery 16 or from any other source of electric energy and the doll is adapted to be

mounted on a mat 17 carrying members 18 of the glove fasteners 19 which when attached to each other complete a circuit through the battery, the wires 20 and the 60 circuit breaker and the electromagnet 13, energizing the latter and oscillating the tubes 9 and 10 and vibrating the arms 6 to simulate life like movements of the doll, and the latter may be dressed in appropriate clothing which is agitated by the movement and produces a dancing effect. 65

The electromagnet is located in the head of the figure 5 where it may be easily placed and adjusted when required.

It is obvious that other arrangements and modifications may be resorted to without departing from the essential features above described or from the scope of the appended claims.

70 What I claim as new is:

1. In a toy, the combination of a figure, limbs adapted to move sidewise, suspending means for the limbs in the figure, and an electromagnet and circuit for vibrating the 80 suspending means to actuate the limbs.

2. In a toy, the combination of a figure, limbs at the side of the figure and adapted to move laterally, an electromagnet in the figure, an electric circuit, and suspending 85 means for the limbs pivoted to the electromagnet and adapted to be vibrated by it to shift the arms.

3. In a toy, the combination of a figure, limbs adapted to move, telescopic tubes carrying the limbs and adapted to move longitudinally, a spring connecting the pair of limbs, an electromagnet and electric circuit, and an armature carrying the telescopic 90 tubes.

4. In a toy, the combination of a figure, limbs at the side of the figure, a coil spring connecting the limbs, tubes inclosing the spring and separating the limbs, a telescopic tube within the inclosing and separating 100 tubes, an electromagnet, an armature, and a rod depending from the armature and carrying the telescopic tubes.

In testimony whereof I have signed my name to this specification in the presence of 105 two subscribing witnesses, this 15th day of May, 1919.

DAVID ZAIDEN.

Witnesses:

DAVID SNYDER,
JAMES F. DUHAMEL.
